FRAME STRUCTURE FOR WEBBED MATERIAL

Frederick Kautz, Glenolden, Pa.

Application August 15, 1944, Serial No. 549,559

11 Claims. (Cl. 189—84)

1

This application is a continuation, in part, of my pending application on Structural framing elements, filed January 15, 1941, Serial #374,568, now Patent 2,412,618, issued December 17, 1946.

The invention relates generally to a development of frame structures in screens, enclosures, partitions, bins, panels, etc. More particularly, it deals with an arrangement of frame elements in frame supporting web bodies which may be supplied by various kind of meshed material or sheet metal, etc., and to be utilized in structures of aforementioned type.

It has been observed that in conventional varieties of framed mesh or sheet panels, moisture and foreign matter easily collect upon the flat horizontal portions of their frame elements which are usually provided by angle or channel stock including flanges and webs generally set at right angle to the mesh or sheet bodies with transverse portion horizontally extended therefrom. In structures embodying channel stock, the hollow side of the channel bar in an upper frame element is turned upwardly and this recessed portion forms an elongated receptacle wherein foreign matter abundantly collects and which has been sought to correct by closing said hollow side with an additional flat strip. It is believed that said disadvantages are caused, in general, by the rigid and unvarying disposition of the frame elements and portions thereof relative to the web and position of the structure wherein they are incorporated and, in particular, by salient exposure of extreme edge portions of said elements. In exposed vertical frame elements, such salient exposure of edges also impairs the appearance of the structure.

It is therefore one of the main objects of the invention to provide framed web structures embodying novel frame elements having portions arranged in varying relation to the web and the position of said structures in order to reduce stated disadvantages.

It is particularly an object of the invention to provide a disposition of the portions in the frame elements which prevents the collection of moisture or foreign matter thereupon if exposed to weather conditions or set up inside of buildings respectively.

It is another object of the invention to provide an effective preventive against corrosion in exposed structures by said arrangement of the portions in the frame elements.

A further object of the invention is to provide a disposition of the portions in the frame ele-

2

ments which avoids salient exposures of extreme edges for better appearance.

It is still another object of the invention to provide frame elements of welded construction, enabling a more unrestricted arrangement of their portions for stated purpose.

More objects, advantages and features of invention will be apparent from the following description considered in conjunction with the accompanying frame drawings, wherein

Figure 1 is a perspective view of a screen partition panel, partly in section, constructed in accordance with the invention.

Figure 2 is a vertical cross section taken at line A—A in Figure 1.

Figures 3 and 4 are fragmentary perspective views of modifications of Figure 1.

Figure 5 is a perspective view of a screen partition panel partly in section, depicting another form of the invention.

Figure 6 is a fragmentary perspective view of a sheet metal partition panel constructed in accordance with the invention.

Figure 7 is a fragmentary perspective view of a modification of Figure 6.

The invention utilizes the novel frame elements for mesh webs presented in my pending patent application, Serial #374,568, filed January 15, 1941, now Patent 2,412,618, issued December 17, 1946, which in their various forms are essentially concavo-convex in cross section with edges of mesh webs retained in vertex portion of said elements. In present invention, structures of framed webbed material include horizontal or inclined frame elements of aforementioned type having their flange portions downwardly directed relative to position of the structures as a preventive against collection of moisture and foreign matter for stated purpose. In another form of the invention, said frame elements are embodied in upright terminal edgings of such structures, presenting their concave side towards the webbed material. In this manner, the extreme edges of said elements are inwardly directed relative to the structure and, therefore, not saliently exposed.

For a more complete understanding of the invention, reference is now made to the accompanying drawings. In Figure 1 there is shown a webbed structure consisting of a mesh web 10 supported by a marginal frame 11. The structure may represent a section in an extended screen partition or fencing, etc., composed of abutted and united sections of like construction progressively extended from each other, or, such struc-

ture may be used as single units for window guards, various other guards and enclosures, bin constructions, etc. The mesh web 10 may be preferably supplied by a wire screen, expanded metal or other commercial types of meshed material. The frame elements or members in frame 11 are provided by two spaced upright edgings 12 connected by two spaced horizontal members which are represented by a lower edging 13 and an upper edging 14. The lower edging 13 is elevated, in present instance, above level of floor 15 in a building structure and the ends of the lower extensions 16 of the upright edgings 12, which serve as leg supports for the webbed structure, rest on said floor. The cross sectional concavo-convex form of said frame elements in Figure 1 is presented in an execution in which respective flange portions are provided by two flat strip bars having their elongated edge portions disposed at an angle to each other. The upright edgings 12 and the lower edging 13 are each composed of the strip bars 17 with transverse portion thereof set approximately at right angle to each other and the projecting ends of the mesh 10 are engaged between the opposed elongated edges of said bars at the vertex portion of the angle thus formed. The upright edgings and the connecting lower edging further have their convex side presented towards the body of mesh 10 and said mesh ends are exposed at the concave side of these members where weld material 18 can be conveniently deposited to unite said ends with contacting edges of bars 17. Thus, said frame elements incorporate an angular body including all the advantages as to strength and rigidity derived from such shape. The upper frame element 14, which is substantially of same construction as the elements previously mentioned, has the concave side presented towards the body of mesh 10 and the projecting ends thereof, engaged between the angular disposed strip bars 17', are exposed at the angle vertex on the convex side of the element. At said location, the angular disposition of the squared edges of strips 17' forms a recess longitudinal of the element 14 wherein the welding material 18' can also be conveniently deposited to unite said mesh ends and strips as shown. In Figure 1, one end of the lower frame element 13 is shown to be abutted to the respective upright element 12 to illustrate the manner in which the frame elements are united to form 11. For such purpose, said end is beveled on a cross sectional line to contact a flange portion of element 12, angular disposed thereto, and welding material 20 is employed to secure said abutted portions to each other. The other respective end portions of frame elements in Figure 1 are shown in section, unabutted to each other, for a better representation of their construction. It is further shown in Figure 1 that the body of mesh 10 lies in a plane equally bisecting the angle of the frame elements resulting in a diagonal disposition of the flanged strips 17 and 17' to said mesh. This, and the alternate relation of the respective faces of the horizontal elements 13 and 14 to mesh 10 provide a downward inclination of the flanges in strips 17 and 17', and it will be obvious that adherence of moisture or foreign matter thereto is reduced by such means. The elongated apertures 19 which remain at vertex of frame elements 12, 13, 14 between the projections of mesh 10 are useful as such an excellent ventilation is provided at underside of the horizontal frame elements in

exposed structures preventing there collection of moisture which, as has been observed, is usually the cause of corrosion in closed members of conventional type. In structures inside of buildings as Fig. 1, the apertures 19 will have no detrimental effect if the horizontal elements, such as 13 and 14, are elevated above level of floor as foreign matter will easily drop through said apertures and collect on the floor below where it may be conveniently removed. In horizontal frame elements resting directly on a floor, other respective means have been designed which will be described hereafter in due order.

The construction of the lower and upper frame elements 13 and 14 is presented in Figure 2 in detail which clearly shows the angular disposition of the strips 17 and 17' and the position of the welding material 18 and 18' in relation to mesh 10, as previously described.

The employment of strip bars in conjunction with welding in said frame elements permits an unrestricted variation in disposition of the portions of said bars relative to a web body like mesh 10 or to entire structure wherein such are employed. For instance, the angular degree of flanges in strips 17 and 17' relative to each other or to mesh 10 may be altered according to desire or need. In Figure 3 a respective modification of Figure 1 is shown embodying a horizontal lower and upper frame element 21 and 22 in which the flanges of strips 23 and 23' lie in a plane parallel to mesh 10 and the flanges of the complementary strips 24 and 24' at an angle to said mesh, resulting in a flush faced structure at one side thereof. The construction and advantages of frame elements 21 and 22 are otherwise the same as such in Figure 1 and they are likewise united by welding material 25 and 25' at respective vertex portions.

In partition structures consisting of framed meshed material in which the lower horizontal frame element is resting directly on a floor of a building structure, the construction shown in Figure 4 may be preferably used. The lower horizontal frame elements 26 in said figure, which corresponds to element 13 in Figure 1, is integrally shaped from a piece of sheet strip bent on a longitudinal medial line so as to dispose transverse section of the elongated flanges 27 at an angle to each other. The angle thus formed is 90° in shown instance which, however, may be subject to variation, as previously indicated. The projecting ends of mesh 10 are received within spaced apertures 28 at vertex portion of element 26 and secured thereto by welding material as indicated at 29. The apertures 28 are further flanked by pairs of outwardly projected tongues 30 formed in the punching operation of the apertures 28 by the junction material of the strip. In the integral element 26, the elongated apertures 19 at vertex portion, such as seen in element 13 of Figure 1, are avoided and foreign matter cannot penetrate, therefore, therethrough to floor 15, as will be appreciated. The substantially weaker element 26 formed of a sheet strip, as compared to frame elements previously described, provides adequate strength when anchored to the floor upon which it is resting. In employing the tongues 30, suitable space is provided for infiltration of the welding material 29 and the additional material formed by said tongues is also useful for absorbing the welding heat which is an essential asset in the thinner material of element 26. If preferred, the ends 75 of mesh 10 may be united with element 26 by

substituting the welding material 29 with electric resistance welding applied upon said tongues and mesh engaged therebetween. As further shown in Figure 4, the lower frame element 26 and the upper frame element 14, of same construction as such in Figure 1, have their flanges diagonally disposed to mesh 10 and downwardly inclined, for the purpose as previously described.

In the modified framed mesh structure of Figure 5, the mesh web 10 is supported within a marginal frame 31 including two spaced upright frame elements 32 concavo-convex in cross section with concave side presented towards the body of mesh 10 in the same manner as the upper element 14 in Figure 1. The upright elements 32 further include the same characteristics as referred element 14 with flanges of strip bars 33 equally angular disposed to each other and ends of mesh 10 engaged between respective edges of said bars and secured thereto by welding material 34 deposited at apex of said elements. The remaining lower and upper horizontal frame elements 35 and 36 in Figure 5 are of identical construction as the corresponding elements 13 and 14 in Figure 1 and embody respectively sets of angular disposed strip bars 37 and 37' and welding material 38 and 38' deposited at respective locations to unite mesh 10 with said bars, as previously indicated, and further, the elements 35 and 36 have also their respective convex or concave side presented towards body of mesh 10 for the purpose, as previously stated. The extreme edge portions in the upright elements 32, arranged as shown in Figure 5, are inwardly presented relative to margin of frame 31 and, therefore, salient exposure of said edges is avoided which may be considered a contribution to a better appearance of entire structure in which such frame elements are incorporated. These elements, such arranged, are preferably intended to serve as freely exposed terminal edgings or posts, unattached to other webbed panel structures or walls of buildings, and in shown example of Figure 5, the framed mesh web structure may be used to advantage as a single unit, as for instance, in window guards, etc. In extended wall partition structures composed of sectional framed units and including a freely exposed terminal, the framed mesh unit of Figure 5 may be employed in a modified form as the respective terminal section. In such cases, one upright element 32 may be substituted by one like 12 in Figure 1, with convex side turned towards body of mesh 10, which will be more suitable for abutment with other units of like construction.

The Figures 6 and 7 show structures substantially of the type presented in Figures 1 and 3 but having the meshed material substituted by a sheet metal web 39. The features and advantages of framing a sheet metal web with described frame elements of concave-convex cross sectional contour remain the same as previously indicated. In Figure 6, the upright edging 40 and the lower and upper horizontal edgings 41 and 42 correspond to the respective elements 12, 13, 14 in Figure 1. The upright and the lower edgings 40 and 41 have their convex side turned towards the body of sheet 39 and embody described angular arrangement of strip bars, indicated by the reference character 43 in this instance, and edge portions of the sheet 39 are likewise engaged between respective elongated edge portions of bars 43 where welding material 44 is deposited within the channel side of said elements to unite the contacting portions. The

upper edging 42, with concave side presented towards body of sheet web 39 and downwardly inclined flanges as element 14 in Figure 1, is of like construction and respective edges of bars 43' are welded to the edge of sheet 39 at apex of said edging as indicated at 44'. In the modified form of Figure 7, the lower and upper horizontal edgings 45 and 46 include a strip bar 47 and 47' respectively with flange portion laid in parallel relation to sheet web 39 and the flange of complementary strip bars 48 and 48' angular disposed thereto. The edges of sheet web 39 are also secured by welding to presented edges of said bars at shown locations as indicated at 49 and 49' respectively. Described structure may serve a similar purpose as such of Figure 3. It should be understood that the framed sheet metal structures of Figures 6 and 7, which embody the downwardly directed flanges in the horizontal frame elements as shown in combination with meshed material, may also incorporate various applications of described upright frame elements, such as 12 in Figure 1 and 32 in Figure 5 or similar forms.

While I have shown and described preferred constructions of the invention, this is by way of illustration only, and it should be understood that referred frame structures may further include frame elements of a type other than shown combined with the frame elements of the invention which may be also subject to changes as to size, proportions, location, their various disposition of the sides thereof, etc., as deemed advisable and, according to the discretion of the user. In this respect, I consider as my own all such modifications in structure as fairly fall within the scope of the appended claims.

I claim:

1. A device of the character described having a web body and a structural support therefor, said support including a combination of elongated support members having sides disposed substantially convergently towards the vertices of said members, said web having respective end portions sustained by said members and the body portion extended therefrom, each of said members having at least one of said sides disposed in substantially diagonal relation to the web and the vertex located substantially in the plane thereof, and said support including at least two members of said defined construction, one having the convex face formed substantially by said convergent sides directed towards the body of the web and another having said convex face directed away therefrom.

2. A structural device having a web body and a structural support therefor, said support including an elongated lower and upper support member having sides disposed substantially convergently towards the vertices of said members, said web having respective end portions secured to said members and the body portion extended therefrom, each of said members having at least one of said sides disposed in substantially diagonal relation to the web and the vertex located substantially in the plane thereof, and each of said members having the convex face formed substantially by said convergent sides directed upwardly relative to the position of said structural device.

3. A device of the character described having a web body and a structural support therefor, said support including a combination of elongated support members having sides disposed substantially convergently towards each other with

at least one side in each member set in diagonal relation to said web, said web having respective end portions engaged between said sides at the vertices of said members and the body portion extended therefrom, and said support including at least two members of said defined construction one having the convex face formed substantially by said convergent sides directed towards the body of the web and another having said convex face directed away therefrom.

4. A structural member having a web body and a frame support therefor, said support having a combination of frame members in which a lower and upper member complement spaced upright members, said lower and upper member each being concavo-convex in transverse section with lateral sides thereof disposed in substantially diagonal relation to said web in a manner so as to be downwardly inclined from the vertices formed by said concavo-convexity and relative to the position of said structural member, and respective end portions of said web being engaged between said sides at the vertices of said lower and upper member and secured therebetween by welding respective parts to each other.

5. A structural member comprising a web body supported within a frame having a combination of frame members in which an upright member is of angular form in transverse section with lateral flanges disposed at an angle to each other, said web having an end portion engaged between said flanges at the vertex of said member and the body portion extended therefrom, welding employed to unite said end with said member at contacting portions, and said member having at least one flange disposed at an angle to said web and further having the concave face disposed towards the body of said web, another member of like construction having its convex face disposed towards the body of said web.

6. The structure of claim 1 in which said member having said convex face directed away from the web is positioned upright in said device.

7. The structure of claim 1 in which one of said convergent sides in each of said members lies in a plane parallel to said web.

8. The structure of claim 1 in which at least one of said support members includes a multiplicity of spaced apertures at the vertex thereof, said web body being defined by a mesh web with pro-

jected end portions spaced from each other and with respective spaced end portions engaged within said apertures, and the support member with said apertures being disposed as a lower member in said structural support with said convex face directed towards said mesh web and upwardly relative to the position of said device.

9. A structural device comprising a web body and a frame support therefor and having elongated frame members being concavo-convex in transverse section, said web having respective end portions engaged within the vertex portions of said frame members formed by said concavo-convexity and the body portion extended therefrom so as to provide sections in each of said frame members at opposite sides of the plane of said web lying in lateral relation to each other, at least one of said sections in each of said frame members having the transverse extension disposed in substantially diagonal relation to said web, and one of said frame members having the convex face directed towards the body of said web and another having the concave face directed thereto.

10. The structure of claim 9 in which said end portions of the web are extended through said vertex portions to the concave and convex faces of said frame members respectively, welding material employed to secure said end portions to said frame members, and said welding material being located substantially at the faces of said frame members lying away from the body of the web.

11. The structure of claim 4 in which said lateral sides in said lower and upper member are disposed respectively substantially in diagonal relation and in planes parallel to said web in a manner so as to be downwardly directed from said vertices and relative to the position of said structural member.
